UNITED STATES PATENT OFFICE.

CHARLES BALOUGH, OF SPRINGFIELD, OHIO, ASSIGNOR TO THE KELLY-SPRINGFIELD MOTOR TRUCK COMPANY, OF SPRINGFIELD, OHIO, A CORPORATION OF OHIO.

ENGINE-GOVERNOE.

1,137,110.

Specification of Letters Patent. Patented Apr. 27, 1915.

Application filed November 7, 1913. Serial No. 799,794.

To all whom it may concern:

Be it known that I, CHARLES BALOUGH, a citizen of Austria-Hungary, residing at Springfield, in the county of Clark and State of Ohio, have invented certain new and useful Improvements in Engine-Governors, of which the following is a specification.

My invention relates to improvements in governors for internal combustion engines, and relates more particularly to improvements in that type of governor which employs a series of loose balls acting in connection with a spring-pressed inclined movable part so that as centrifugal force is developed in the balls by the motion of the engine, they will act upon the inclined part to move the same against the tension of its spring to regulate the supply of explosive mixture.

The object of my invention is to simplify and make more effective the operation of governors of this character.

A further object of my invention is to provide a construction which will permit a practically instantaneous opening of the regulating valve for the explosive mixture when an increased load is placed upon the engine.

30 A further object is to provide a construction which will eliminate undue friction between the balls and their coöperating parts.

In the accompanying drawings,—Figure 1 is a vertical sectional view of a governing device and regulating valve showing my improvements. Fig. 2 is a side view of the regulating valve, a portion of the inclosing casing for the same being removed. Fig. 3 is a section on the line 3—3 of Fig. 1. Fig. 4 is a detail of the operating balls and their holder.

Like parts are represented by similar characters of reference throughout the several views.

45 The particular purpose for which I have designed this governor is to regulate the explosive charge for internal combustion engines used in connection with automobile trucks. It is desirable that the speed of these trucks be kept within certain limits and it has become usual therefore to equip the motors with governors. Difficulty has been experienced, however, in governing the

speed of truck motors in that the governors heretofore employed have not been sensitive enough; that is, the action of the governor begins too early and stops too late. By this is meant that it is desirable that the governor permit the engine to acquire a certain desired speed before its action upon the regulating valve begins, as in connection with starting the motor, and that after the speed of the motor has been reduced to a certain limit, it is further desirable that the action of the governor cease practically instantaneous, as when the motor encounters a sudden heavy load such as a steep hill. It has been found that the employment of loose balls in which centrifugal energy is stored by the motion of the parts, tends to overcome these difficulties, for it has been demonstrated that these loose balls will not move from their normal position until a certain amount of centrifugal energy is stored up in them by the speed of the motor reaching a certain point, and that additional load on the motor will very quickly effect these loose balls so that the instant they lose the accumulated energy, they will roll back to their starting position and thus accomplish a very quick opening of the regulating valve and thereby allow the motor to quickly pick up and carry the increased load.

In the said drawings, 1 represents a sectional casing in which the governor devices are located; this casing being secured to any suitable point of the motor. Located in bearings 2 and 3 in this casing is a vertical shaft 4, adapted to be driven from the engine through the medium of the shaft 5 and gears 6 and 7. Connected with this shaft 4 just above the bearing 2, is a ball holder provided with a series of radially-arranged pockets 8^a in which are located a series of balls, 9; the said pockets being each of substantially the same width throughout and confine the balls therein more or less snugly but allow the balls to turn freely therein. These balls run upon a race or track 10 in the nature of a hardened ring, which loosely encircles the holder 8 just beneath the pockets therein and is supported by ball bearings 11 located in a ball-cage 12, which balls 11 run upon the projecting flange 2^a of the bearing 2. The upper part of the shaft 4 is reduced, and, slidably

mounted upon this reduced portion of the shaft and also in the upper portion of a supporting bridge or diaphragm 13, is a tubular stem 14, having connected to an extended 5 flange 14^a at the lower end thereof a cup-shaped plate 15 having an inclined outer wall 15^a. A spring 16 encircling the stem and bearing against the flange 14^a at its lower end and at its other end against an 10 in-turned flange at the upper end of an adjusting nut 16^a, causes the cup-shaped plate to be forced yieldably against the balls 9. The tension of the spring may be regulated by the adjusting nut 16 before referred to.

15 The upper end of the tubular stem 14 has a slot or bifurcated portion across which extends a pivot pin 17 engaged by the bifurcated arm 18 of a bell-crank lever pivotally 20 supported in ears 19 projecting upwardly from the support 13. The other arm 20 of this bell-crank lever is pivotally connected to one end of a link 21, the opposite end of said link being pivotally connected to a 25 crank arm 22 fast to a shaft 23 which extends to and is connected with the regulating valve located in the intake manifold 24; the shaft having a bearing at one end in the casing 1, and in a removable plug 24^a in the 30 manifold at the other end.

35 This regulating valve is of the butterfly type consisting of a shaft 27 having projecting wings 25 and 26; the said shaft being journaled in the wall of the manifold 40 and plug 24 and has a tongue and groove connection with the shaft 23. The valve is of peculiar construction, in that the wing 25 thereof is of greater length than the other wing 26 and the valve shaft is journaled eccentrically in the intake manifold 45 to compensate for the different lengths of the wings. In the open position of the valve, the long wing 25 projects upwardly and the short one 26 downwardly, so that as 50 the valve starts to open, the inrush of the mixture will have a tendency to assist the opening of the valve by reason of the fact that the long wing gives a greater leverage for the action of the inrush fluid than does the shorter wing.

55 It is thought that the operation of the device will be understood. As before stated, it is necessary that the engine acquire a certain speed before enough centrifugal energy is stored up in the balls 9 to cause them to roll outwardly. As these balls move outwardly, they will, by reason of their action upon the inclined surface 15^a of the plate 15, force said plate and its tubular rod 60 upwardly against the tension of the spring 16. This causes the regulating valve to move to closing position through the connections described. When a sudden heavy load is encountered and the speed of the parts is 65 reduced so that the centrifugal energy in the

70 balls is reduced, they will have a tendency to roll back to their normal position very quickly, and this, together with the action of the inrush fluid upon the valve, will cause the valve to open very quickly, thus enabling the motor to take care of the increased load.

75 By this connection it will be seen that undue friction between the balls and their co-operating parts is eliminated, due to the employment of the rotatable track 10, since it will be seen that as the member 8 revolves, the balls 9 will be caused to rotate upon their own axis by the frictional engagement therewith of the cup 15, and that the rotation of the balls will cause the track 10 to revolve upon the bearings 11, whereas in prior constructions where loose balls have been employed for this purpose, it has been necessary for the balls to slide upon certain of their co-operating parts, such as the pockets of the member 8.

80 A further advantage of this governor resides in the fact that it has no small pivots to get out of order, and further that the 85 tension of the spring 16, the tension of which restricts the centrifugal force of the balls, may be regulated, while the governor is running.

85 A further advantage resides in the fact 90 that the track 10 may be readily removed when desired and another track of different shape substituted therefor. In explanation of this, it may be said that the shape of the track 10 has a decided effect on the workings 95 of the governor and said governor can be made to care for a certain speed at a certain position, or it can work pendulum like from the utmost inner to the utmost outer position 100 backward and forward, all depending upon the top surface of the track 10 as to whether it is perfectly straight, such as shown in the drawings, or is convex or concave to a more or less degree.

105 A further advantage in the construction 110 described is that the governor may be run in an oil bath and in this way prevent any appreciable wear. It also has the advantage that it may be constructed compactly and so completely inclosed as to eliminate the 115 danger of dust or other undesirable substances coming in contact with the working parts and to also eliminate the danger of the parts getting out of order by tampering.

120 Having thus described my invention, I claim:

1. In a governor, a revoluble member having a series of pockets, balls located in said pockets, a revoluble track for said balls, an anti-friction support for said track, and a movable member co-operating with said balls.

125 2. In a governor, a revoluble member having a series of radially-arranged pockets open on their under sides, a series of balls in said pockets, a movable circular track 130

- for said balls, an anti-friction support for said track, and a slidably-arranged plate having an inclined surface coöperating with said balls together with means for holding the same in frictional engagement therewith. 5
3. In a governor, a revolute shaft, a member connected with said shaft having a series of radially-arranged pockets open on their under sides, a series of balls in said 10 pockets, a movable track for said balls, an anti-friction support for said track, and a movable member coöperating with said balls together with a spring for holding the same in frictional engagement therewith.
- 15 4. In a governor, a revolving member having a series of radially-arranged pockets open on their under sides, a series of balls in said pockets, a track for said balls, and an anti-friction support for said track, said 20 track being capable of moving independent of said pocketed member, and a movable spring-pressed member coöperating with said balls.
5. In a governor, a revolute shaft, a member connected with said shaft having a series 25 of radially-arranged pockets open on their upper and under sides, a movable track on the under side of said pockets for said balls, an anti-friction support for said track, a 30 movable member on said shaft above said pockets, and a spring for holding said movable member in frictional engagement with said balls.
6. In a governor, a revolute shaft, a longitudinally-movable member connected with 35 said shaft having a series of radially-arranged pockets open on their upper and under sides, a movable track for said balls on the under side of said pockets, an anti-friction support for said track, a movable member 40 having an inclined face coöperating with said balls, a hollow stem connected with said movable member, and a spring about said stem to hold said movable member in frictional engagement with said balls. 45
7. In a governor, a revolute shaft, a member connected with said shaft having a series of radially-arranged pockets open on their upper and under sides, a series of balls 50 in said pockets, a movable track beneath said pockets for said balls, an anti-friction support for said track, a hollow stem slidably mounted on said shaft, an inclined plate connected with the lower end of said 55 stem, a spring for holding said plate in frictional engagement with said balls, and
- means for adjusting the tension of said spring.
8. In a governor, two members yieldably held together but capable of being separated, a series of balls confined between said members but capable of moving outwardly under centrifugal force to separate said members, means for revolving said balls about a common central axis, one of said 60 members having movement relative to said balls so that all sliding frictional engagement between said balls and separable members is eliminated.
9. In a governor, two members yieldably held together but capable of being separated, one of said members consisting of a rotatable track, a series of balls confined between said members but capable of moving outwardly under centrifugal force to separate 65 said members, means for revolving said balls about a common central axis, whereby all sliding frictional engagement between said balls and separable members is eliminated.
10. In a governor, two members, one of which is spring-pressed toward the other and one of which consists of a rotatable track, a rotatable ball holder between said members, a series of balls confined between 70 said members and arranged to be revolved about a common axis by said holder, the construction and arrangement of said parts being such that all sliding frictional engagement between said balls and separable members is eliminated.
11. In a governor, two members yieldably held together, a series of balls confined between said members, together with means for revolving said balls about a common 75 central axis, said balls being capable of moving outwardly under centrifugal force, the construction of said members being such that the outward movement of said balls will cause a separation of the same, one of 80 said members being capable of a revolute movement relative to said balls, the construction and arrangement of said parts being such that all sliding frictional engagement between said balls and separable members is eliminated.
- In testimony whereof, I have hereunto set my hand this 30th day of October, 1913.
